(57) CLAIM

The ornamental design for a prayer box, as shown and described.

DESCRIPTION

FIG. 1 is a perspective view of a prayer box, showing my new design;

FIG. 2 is a front view thereof;

FIG. 3 is a rear view thereof;

FIG. 4 is a top view thereof;

FIG. 5 is a bottom view thereof;

FIG. 6 is a right side view thereof;

FIG. 7 is a left side view thereof; and,

FIG. 8 is a cross-sectional view taken along the line 8-8 of FIG. 4.

The broken lines depict portions of the article that form no part of the claimed design.
